CLAIM

The ornamental design for a turning peel, as shown and described.

DESCRIPTION

FIG. 1 is a perspective view of a turning peel in accordance with the present design and showing a handle in a fully extended state;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a top view thereof with the handle in an unextended state; and,

FIG. 9 is a top view thereof with the handle in a disassembled state.

The elements shown in broken lines in the Figures form no part of the claimed design.
